UNITED STATES PATENT OFFICE

FRITZ KAYAN, OF LYNDHURST, NEW JERSEY

DESIGN FOR A JAR OR SIMILAR RECEPTACLE

Application filed August 13, 1930. Serial No. 36,654. Term of patent 3½ years.

To all whom it may concern:

Be it known that I, FRITZ KAYAN, a citizen of Germany, residing at Lyndhurst, in the county of Bergen and State of New Jersey, have invented a new, original, and ornamental Design for Jars or Similar Receptacles, of which the following is a specification, reference being had to the accompanying drawing, forming part thereof.

In the drawing—

Figure 1 is a top plan view of a jar or similar receptacle, showing my new design; and

I claim:

The ornamental design for a jar or similar receptacle, as shown.

FRITZ KAYAN
